UNITED STATES PATENT OFFICE.

LEDYARD COLBURN, OF BIRMINGHAM, CONNECTICUT, ASSIGNOR OF ONE-HALF TO RICHARD R. COLBURN, OF SAME PLACE.

ELECTRIC-ARC LAMP.

SPECIFICATION forming part of Letters Patent No. 316,240, dated April 21, 1885.

Application filed March 13, 1884. (No model.)

To all whom it may concern:

Be it known that I, LEDYARD COLBURN, of Birmingham, in the county of New Haven and State of Connecticut, have invented a new

5 Improvement in Electric-Arc Lamps; and I do hereby declare the following, when taken in connection with accompanying drawing, and the letters of reference marked thereon, to be a full, clear, and exact description of the same, 10 and which said drawing constitutes part of this specification, and represents a sectional side view showing the two carbons of an arc lamp with the gas-jet and air-jet arranged independent of the carbons.

15 This invention relates to an improvement in electric-arc lamps, the object of the invention being to reduce the electric current without diminishing the brilliancy of the light; and my invention consists in combining with 20 the carbons of an electric-arc lamp a jet of air and gas impinging directly upon the points of the carbons, so that the air and gas will mingle at those points and produce an intense heat upon the points, and whereby the elec-

25 tric current may be reduced to the extent that the carbons are heated by the gas, as more fully hereinafter described.

A represents one carbon and B the other carbon of a common arc lamp, to each of which 30 the lines are led to form the arc between the points of the two carbons.

C is a contracting tube, terminating near the points of the carbon; D, a like tube, preferably arranged directly opposite the point of the tube

C. To one of the tubes—say C—gas is supplied, and to the other tube, D, air is supplied, the quantity of air and gas being regulated by cocks E or otherwise.

When the circuit is closed and the arc formed between the two burners, the gas is supplied 40 through the tube C, and instantly ignites. At the same time air is introduced through the other tube, D, in sufficient quantity to mingle with the gas and produce perfect combustion. Therefore this combined gas and air produces 45 an intense heat directly at the points of the carbons, and which, with a greatly-reduced electric current, will heat the carbons to a point of brilliancy equal at least to the most brilliant effect produced by the usual strong 50 electric current.

The air and gas may be supplied by any device which will deliver them under the requisite pressure.

I do not claim, broadly, supplying mixed gas 55 and air at the points of the electrodes, as such, I am aware, is not new.

I claim—

In an electric-arc lamp, the combination of the two carbons A B with the tubes C D, applied to direct, respectively, a gas and an air jet between the points of the carbons, substantially as described.

LEDYARD COLBURN.
